UNITED STATES PATENT OFFICE.

HUGH L. BOY, OF SPEERS FERRY, VIRGINIA.

RAILWAY-TIE.

1,211,068.

Specification of Letters Patent.

Patented Jan. 2, 1917.

Application filed June 18, 1916. Serial No. 104,024.

To all whom it may concern:

Be it known that I, HUGH L. BOY, a citizen of the United States, residing at Speers Ferry, in the county of Scott and State of Virginia have invented certain new and useful Improvements in Railway-Ties; and I do hereby declare the following to be a full, clear, and exact description of the invention, such as will enable others skilled in the art 10 to which it appertains to make and use the same.

This invention has for its object to provide a metallic sheath or casing adapted to embrace an ordinary wood railway tie for 15 protecting the latter and provided with means for rigidly securing the track rails in position thereon.

Another object is the provision of an improved railway tie which is so constructed as 20 to support practically the entire weight of the track rails upon the wood part of the tie.

With these and other objects in view, the invention consists in the novel construction, combination and arrangement of parts as will 25 be hereinafter specifically described, claimed and illustrated in the accompanying drawing, in which:

Figure 1 represents a plan view of the improved tie, Fig. 2 represents a side elevation thereof, partly in section, and Fig. 3 represents a transverse section taken on the line 3-3 of Fig. 2.

Referring to the drawing in detail, wherein similar reference numerals designate corresponding parts throughout the several views, the numeral 5 indicates the well known type of wood tie and 6 designates generally the improved casing or seat, which is preferably constructed of metal and includes the top plate 7 and the spaced depending flanges 8, which practically inclose the wood tie 5 and protect the latter. The top plate 7 of the casing or seat 6 is secured to the tie 5 by bolts 8, or equivalent means.

Adjacent each end of the plate 7 are formed a pair of integral spaced enlargements 9, having inwardly directed and horizontally disposed flanges constituting holders for a pair of rail clamps 10, the inner 50 surfaces of which are suitably shaped so as

to embrace the base and adjacent web portion of the track rail 11. Portions of the depending flanges 8 lying between each pair of enlargements 9 are cutaway, as indicated at 8^b, so as to expose the adjacent portion of 55 the tie 5, which latter supports the weight of the clamping members 10 and the track rails 11.

The clamping members 10 are moved inwardly into operative engagement with the 60 rails 11 by adjustable screws 12 threaded in internally screw threaded apertures formed in the enlargements 9 and having headed outer terminals to facilitate adjustment thereof. The inner terminals of the screws 65 12 engage the clamping members 10 and are locked in adjusted position by lock nuts 13 fitted upon the screws and engaged between the enlargements 9 and the clamping members 10.

What I claim is:

1. A railway tie comprising a wooden tie, a metallic casing embracing said tie, pairs of enlargements arranged adjacent the opposite ends of said casing, the portions of 75 said casing intermediate the enlargements of each pair being cutaway, and rail clamping members supported upon said wooden tie and engaged between the pairs of enlargements.

2. A railway tie comprising a wooden tie, a metallic casing including a top plate and spaced depending flanges carried thereby embracing said wooden tie, a pair of enlargements formed adjacent each end of said 85 casing, a pair of clamping members arranged between the enlargements of each pair, the portions of said casing intermediate said enlargements being cutaway, adjusting screws threaded in such enlargements and 90 engaging said clamping members for holding the latter in operative position, and means to lock said screws in adjusted position.

In testimony whereof I affix my signature 95 in presence of two witnesses.

HUGH L. BOY.
